UNITED STATES PATENT OFFICE.

MARGARET A. MATTSON, OF COLLINGSWOOD, NEW JERSEY.

BREAST-SHIELD.

1,094,158.

Specification of Letters Patent. Patented Apr. 21, 1914.

Application filed July 8, 1913. Serial No. 777,818.

To all whom it may concern:

Be it known that I, MARGARET A. MATTSON, a citizen of the United States, residing at Collingswood, in the county of Camden and State of New Jersey, have invented certain new and useful Improvements in Breast-Shields, of which the following is a specification.

The object of my invention is to provide a novel, simple and efficient breast shield for nursing mothers, which may be held in place without difficulty and which may be worn with ease and comfort and which will absorb the milk discharged from the breast of the wearer, as will be hereinafter fully described and particularly claimed.

In the accompanying drawings, illustrating my invention: Figure 1, is a perspective view of my improved breast shield. Fig. 2, is a view of the forward portion of the belt and parts carried thereby as seen from the inside of the belt. Fig. 3, is a horizontal section through the parts shown in Fig. 2, on line 3—3 of Fig. 2. Fig. 4, is a view of a modified form of parts shown in Fig. 2. Fig. 5, is a vertical section, on line 5—5 of Fig. 1.

Referring to Figs. 1, 2, 3 and 5 of the drawings, 2 designates a belt adapted to extend around the body of the wearer. The ends of the belt 2 terminate in elastic portions 4 and 6; and the elastic portion 4 is provided with a suitable buckle 7 adapted to engage the elastic portion 6 in any suitable position, as the belt is adjusted to properly fit the body of the wearer.

To prevent accidental downward displacement of the belt 2, I provide the same with shoulder straps 8 having their rearward ends secured to the rearward portion of the belt 2 and having their forward ends adjustably attached to the forward portion of the belt 2 by means of suitable buckles 9. These straps 8 are adapted to extend over the shoulders of the wearer and to be adjusted on the buckles 9 to fit the wearer.

In front of the forward portion of the belt 2 is an elongated horizontally-extending pouch 10 having a forward wall 11 and a rearward wall 12, each formed of waterproof fabric or other suitable flexible material which will hold liquid.

The end and bottom edges of the walls 11 and 12 outwardly of and below the points 13 and 14 are secured together and the upper portions of the front and back walls

11 and 12 are open between the points 13 and 14. This opening in the top of the pouch is closed by a flap 15 forming a continuation of the rearward wall 12 and extending down in front of the forward wall 11. The closing flap 15 is held normally in the position shown against the front wall 11 by means of suitable buttons 16. In the present embodiment of my invention, I secure the end and bottom edges of the front and back walls 11 and 12 together by means of a binding strip 17 which embraces the edges of the fabric forming the walls 11 and 12 and extends from the point 13 around the ends and bottom of the pouch to the point 14 and is sewed to the fabric forming the walls by a line of stitching 18. I also sew a binding strip 19 around the free edge of the flap 15.

The forward portion of the belt 2 is provided with two spaced and suitably located openings 20 adapted to receive the breast nipples of the wearer; and the rearward wall 12 of the pouch 10 is provided with two similar openings 21 in registry with the openings 20, so that when the belt is properly placed around the body of the wearer, the breast nipples may project through the openings 20 and 21 to the interior of the pouch 10. The edges of the fabric forming the rearward wall 12 around the openings 21 therein is secured to the edges of the fabric forming the belt 2 around the openings 20; and, as a suitable means for this purpose, I provide binding strips 22 which extend around the edges of the fabric forming the openings 20 and 21 and which embrace the said edges and which are sewed to the fabric of the wall 12 and the fabric of the belt 2 by lines of stitching 23.

Within the pouch 10 is located a layer or layers of absorbent material 24 which extends from top to bottom and from end to end of the pouch and across the openings 20 and 21, so that when the device is applied to the wearer the ends of the breast nipples may come into contact with the absorbent material 24 to permit the material 24 to absorb the discharged milk.

The pouch 10 is secured to the belt to be supported thereby only around the openings 20 and 21, all other portions of both the forward wall 11 and rearward wall 12 of the pouch being free to move relatively to the belt. This is an important feature of my invention, as it enables me to hold the belt

comparatively firm upon the body of the wearer to retain the openings 20 and 21 in proper registry with the breast nipples, and, at the same time, it permits free adjustment 5 of the pouch relatively to the belt, under the influence of the movements of the body of the wearer relatively to the clothing, between which and the body of the wearer the pouch is located. This is particularly 10 true when corsets are worn and the pouch is worn adjacent to the upper portion of corsets or between the body and the upper portion of the corsets.

Another important feature of my invention 15 is in having the two nipple-receiving openings communicate with a single pouch for the reason that should there be an unequal discharge of milk from the two breasts of the wearer, the milk may distribute itself 20 throughout the pouch.

In Fig. 4 I have shown a modification wherein I have raised, at 25, the central portion of the bottom of the pouch 10, forming, in effect, two communicating pockets for the 25 absorbent material. This form of the invention may be found desirable when clothing and other conditions require it.

I claim:

1. In a breast shield, a belt adapted to 30 extend around the body of the wearer and having spaced nipple-receiving openings in the forward portion thereof, a pouch extending horizontally across the space between the belt openings and having nipple- 35 receiving openings therein in registry with the belt openings, means for attaching the

belt to the pouch, and absorbent material within the pouch and extending from a position in front of one of said openings in the pouch to a position in front of the other of 40 said openings in the pouch.

2. In a breast shield, a belt adapted to extend around the body of the wearer and having spaced nipple-receiving openings in the forward portion thereof, a pouch having a 45 rear wall extending horizontally across the space between the belt openings and having nipple-receiving openings therein in registry with the belt openings, means for attaching the edges of said rear wall around the openings therein to the edges of the belt around the openings therein, and absorbent material 50 within the pouch.

3. In a breast shield, a belt adapted to extend around the body of the wearer and having spaced nipple-receiving openings in the forward portion thereof, a pouch having a rear wall extending horizontally across the space between the belt openings and having nipple-receiving openings therein in registry 55 with the belt openings, binding strips extending around and embracing the edges of said rear wall and said belt around the openings therein and stitched thereto, and absorbent material within the pouch.

In testimony whereof I affix my signature in presence of two witnesses.

MARGARET A. MATTSON.
